CLAIM

The ornamental design for a combined shelf bracket and mounting plate, substantially as shown and described.

DESCRIPTION

FIG. 1 is a perspective view of a combined shelf bracket and mounting plate showing my new design;

FIG. 2 is a side elevational view, the side opposite being a mirror image thereof;

FIG. 3 is a top plan view thereof;

FIG. 4 is a bottom plan view thereof;

FIG. 5 is a rear elevational view thereof;

FIG. 6 is a front elevational view thereof;

FIG.1

FIG.5

FIG.6
